DES. 2456

Letters Patent No. 2456 Dated Sept. 25. 1866.

Design for a Trade Mark

In Schedule referred to by these Letters Patent and making part of the same

to all whom it may concern:

Be it known that I, Edward S. Peugot of Chicago in the County of Cook and State of Illinois have invented and originated a new Design for Trade Mark for Retailing String Boxes; and I do hereby declare that the following is a full, clear and exact description of the same, reference being had to the annexed drawings and letters of reference marked thereon, making a part of this Specification in which:

Fig. 1, is a representation of my trade mark. The object of my invention is to provide a simple and suitable device which may be printed or stamped on labels to be secured to boxes in which retail strings are kept for sale, in order that such goods may be distinguished from other goods of similar kinds in Market. It represents a cross, surrounded by three rays, B, projecting outwards on all sides. C, C, three circular lines terminating at the shield D, and wreath E, and enclosing three rows of flowers F, F. In the open space enclosed by the wreath E, and on the shield D, is to be printed letters, or numbers, designating the kind of string contained in the box.

Having thus described my device, what I claim as my invention and desire to secure by Letters Patent of the United States is the Design for a Trade Mark, herein set forth and shown,
